UNITED STATES PATENT OFFICE.

JULIUS KELLER, SR., OF CHICAGO, ILLINOIS.

BRUSH GEAR FOR VACUUM CLEANERS.

Application filed April 6, 1925. Serial No. 20,900.

This invention relates to brush gearings for vacuum cleaners and the like and the essential object is to provide a simple and compact brush gearing wherein there is a 5 geared connection from traction driving wheels to the brush and in which the wheels may be raised and lowered with reference to the brush while the geared connection and the position of the brush relative to the nozzle of the cleaner is maintained.

A further object is to provide a brush gearing in which the bearings and driving gears are protected against contact by dust and foreign matter, the protecting arrangement also serving to retain an adequate quantity of lubricant for the bearings and gears.

My invention as shown is adapted to occupy a position forwardly of a cleaner, the brush being mounted in rigid bearings formed by a portion of the vacuum cleaner casing while the traction wheels which are adapted to have a geared connection with the brush to drive it are preferably mounted on separate frames, pivoted about the axis of the brush and capable of being held in various positions relative to the nozzle and brush.

Other objects and features of my invention will become apparent in the further description which relates to the accompanying drawings. The essential characteristics will be summarized in the claims.

In the drawings Fig. 1 is a sectional plan taken through the nozzle portion of a vacuum cleaner adapted to receive my brush gearing; Fig. 2 is a transverse section showing the height adjustment for the driving wheel taken along a plane indicated by the line 2—2 on Fig. 1; Fig. 3 is a transverse section along a plane indicated by the line 3—3 on Fig. 1; Fig. 4 is another transverse section taken along the line 4—4 on Fig. 1.

Referring in detail to the drawings and indicating the various parts by numerals—1 indicates the forward or nozzle portion of a vacuum cleaner casing. The nozzle may have end walls 2 and 3, front and rear walls 4 and 5 and partition members 6 and 7, portions of which are shown as formed integral with the rest of the casing to provide separate chambers for enclosing the driving mechanism for the brush.

The support for the brush 10, may comprise in part removable plates 11, which form part of the respective partitions and

which have recessed bearing supporting portions 12 arranged to slide into slots 9 in the partitions 6 and 7. The plates may be secured in any convenient manner, as by inwardly projecting flanges 13. One of these flanges is shown in Fig. 4 as being secured by screws to boss portions 14 on the interior of the casing.

Tubular bearing members 15 may be rigidly secured to each member 11 as by a shoulder 16 engaging one side of the recessed portion of the plate and a riveted over portion 17 engaging the other side. Short shafts 19 extend through each of the bearing members 15, which shafts may carry squared projections 20 and 27 each adapted to engage a square socketed ferrule 32 secured to each end of a shaft 30 for the brush.

At one end (the right as shown in Fig. 1) the projection comprises a member 20 slideable on the squared end of the shaft 19. The member 20 is forced toward the brush by a spring 35 bearing against a cupped portion 21 of the member 20 and shown as reacting against a portion of the shaft 19. This member 20 may be prevented from coming entirely off the end of the shaft when the brush is removed by a cap screw 22 in the end of the shaft.

The ferrules may loosely fit the projections 20 and 27 so that when the spring 35 is compressed by the end-wise movement of the brush (a right hand movement as shown in Fig. 1), the brush may be entirely removed by being swung downwardly clear of the projection 27.

One of the principal characteristics of my invention is that by very simple retaining means oil is retained in adequate quantities in the working parts of the mechanism while the same retaining means prevents the ingress of dust.

To this end I have shown each shaft as provided with a flange 23, the outwardly turned edges of which are arranged to receive a dust ring of any suitable fibrous material which may bear against the recessed portion of the plate 11 and effectually prevent the ingress of dust to or escape of oil from the bearing for the shaft. To more completely isolate the bearings from dust, I may employ tubular hood members 25 seated in the recessed portions of the members 11, the member 25 at the right hand end of the shaft (as shown in Fig. 1) also providing a chamber for the spring 35.

The tubular bearing 15 as well as providing a rigid support for the shaft 19 also provides on its exterior a rigid pivotal mounting for a circular member or disc 43 which 5 carries a cup shaped traction wheel 40 having friction bands 41 for engaging the surface to be cleaned. Means which will be later described provides for raising and lowering this disc by turning it up or down on its 10 pivot and consequently raising or lowering the wheel with reference to the nozzle. During this turning, by reason of the pivotal mounting about the axis of the brush shaft, the original relation between the brush and 15 nozzle is maintained.

The means for preventing the escape of lubricant and ingress of dust with reference to the driving wheel and the disc 43 and the parts therein contained preferably 20 comprises a groove 44 about the periphery of the disc 43 which is adjacent an inturned flange 45 of the cup-shaped driving wheel, these parts being in overlapping relation, as shown in Fig. 1. The groove and the flange 25 provide a closed recess into which a felt ring 46 is inserted in the usual manner previous to final assembly.

The mechanism for driving the brush shaft includes a short shaft 51 bearing in 30 a sleeve 48 seated in a boss portion 47 of the disc 43. The shaft 51 has a reduced extension 52 shown as riveted over the web portion 53 of the wheel 40. A gear 55 concentric with the axis of the wheel is clamped 35 and held tightly against the portion 53 of the wheel by the riveted end of the shaft 51, in position to engage a second gear 56 rigid on the outer end of the shaft 19. Any means may be utilized to prevent the gear 55 from 40 turning relative to the wheel.

In assembling this mechanism the bearing sleeve 15 may be first secured to the plate 11; the disc 43 then slipped over the bearing, the shaft 19 then put into place 45 and assembled with the gear 56; and finally the flange of the traction wheel may be slipped over the peripheral surface of the disc, carrying the gear 55 into mesh with the gear 56.

50 The whole mechanism may be then slid into place and the plate 11 then attached by the flanged overhanging brackets 13 as previously set out.

By reason of the proximity of the riveted 55 end of the shaft 52 to the outer partition 2 or 3, the disk 43 and the wheel 53 and its associated parts are all held together without the use of the pins or screws so long as the plate 11 is in position. The very slight 60 end play which may result from clearance between the riveted ends of the pin 51 and the end walls is negligible.

It will be easily understood from the 65 above description that by swinging the disc 43 about the axis of the shaft 19, either

wheel may be raised or lowered. For raising either wheel independently, I preferably provide resilient arms 47 suitably secured in any manner to the discs as by a key shaped recess 68 and a screw 69. To provide for holding the arms 47 in the desired position, I preferably employ arcuate notched plates 60 each having slots 61, 62 and 63, into which the arms 47 may be sprung as shown in Fig. 1.

In Fig. 2, I have shown the wheels supporting the nozzle of the cleaner slightly off the surface to be cleaned and with the arms in their extreme elevated position best suitable for bare floors or very light nap rugs. 80 The arms would occupy the intermediate notches 62, in case a rug having a heavier nap is to be cleaned and for very heavy nap rugs the lowermost notches 63, are used to hold the nozzle in the highest position 85 shown in Fig. 3. It will be seen that no matter in what position the wheels are held the brush will always remain in the same relative position with the face of the nozzle 90 to produce the desired result.

It will be seen that I have provided a brush gearing for a vacuum cleaner which may be easily and quickly assembled from a minimum number of simply formed parts, one part holding another in place when the gearing is finally fastened in the cleaner casing. Moreover, I have devised a means whereby all the working parts of the gearing may be kept lubricated and free from dust and other foreign matter. By reason of the above characteristics and by reason of my adjustment mechanism whereby the driving wheels may be quickly adjusted to various desired positions by simple resilient arms and rigidly maintained in such positions, I have provided a cleaner nozzle arrangement which will operate satisfactorily under any reasonable conditions. I am aware that changes may be made in the construction and hence I do not wish to limit myself to mere constructional details.

I claim:

1. In a vacuum cleaner in combination, a brush and a driving shaft therefor, a bearing for the shaft, a member pivoted about the axis of said bearing, a driving wheel carried by said member in eccentric relation to the shaft and having a gear, a gear carried rigidly by said shaft and meshing with the first named gear, a resilient arm rigid with the pivoted member and adapted to swing the member to raise and lower the wheel with reference to the brush shaft, said arm projecting through an opening in the casing, and a member rigid with the casing having slots with which the arm is arranged to register to hold the wheel in adjusted position with reference to the brush shaft.

2. In a vacuum cleaner, a nozzle portion

having side and end walls, a transverse partition dividing the nozzle portion, a brush driving shaft, a bearing therefor carried by the partition including a removable plate and a tubular member rigid therewith, a circular member swingably mounted on said bearing, means for adjustably holding the circular member in a plurality of swung positions, a bearing carried by said circular member, and a driving wheel having a geared connection with the brush shaft and having a shaft rigidly secured thereto and journaled in the last named bearing, said wheel having an overhanging peripheral flange fitting over the periphery of the circular member to form a dust proof casing for said geared connection and said wheel shaft bearing.

3. In a vacuum cleaner, a housing member having side and end walls and a partition member, a brush driving gearing supported within the housing by said partition, said gearing comprising a shaft and a bearing therefor, a driving wheel having an overhanging peripheral flange and having a driving connection with said shaft, a member pivoted about the bearing for supporting said wheel in eccentric relation to the said shaft and having the peripheral surface thereof adjacent the flange of the wheel, oil retaining means interposed between said flange and peripheral surface, and an arm carried by the pivoted member having an adjustable resilient connection with one of said housing walls for raising and lowering the wheel and maintaining it in adjusted position.

4. In a vacuum cleaner having a casing, a removably mounted brush, a shaft for rotating the brush, a bearing for the shaft comprising a removable plate rigid with the vacuum cleaner casing and a tubular member rigidly carried by the plate, a circular member supported by the bearing member and adapted to swing about the axis of the shaft, a traction wheel in eccentric relation to the shaft and having a flange overlying the circular member to form a lubricant containing compartment, a bearing support for the wheel carried by the circular member, a geared connection between the wheel and the shaft within the compartment, means for preventing the escape of lubricant from the compartment interposed between the periphery of the circular member and the flange of the wheel and means including an arm rigid with the circular member for raising and lowering the wheel with reference to the brush for holding the wheel in adjusted position.

5. In combination with a vacuum cleaner having a casing, a bearing rigidly supported by the casing, a shaft extending through said bearing, a driving gear rigid on the shaft, a circular member adjustably and

eccentrically mounted to swing about the axis of said shaft and supported by the bearing, a traction wheel concentric with said circular member and supported thereby, a gear rigid with the wheel adapted to drive said first mentioned gear, the circular member and the wheel fitting together in overlapping relation to form a container for the gears in which lubricant for the gears and bearings may be contained, and means interposed between the adjacent peripheral surfaces of the circular member and traction wheel for preventing the escape of lubricant from the container.

6. In combination with a vacuum cleaner, a nozzle portion having an opening adjacent a surface to be cleaned, transverse partitions located within the nozzle portion dividing said portion into chambers, a member removably mounted on one of said partitions, a brush driving shaft carried by the removable member and projecting into a respective chamber, an annular recess formed between the shaft and removable member adapted to receive a dust ring to retain oil and prevent the ingress of dust to the bearing, a member adjustably pivoted about the axis of the shaft, a traction wheel supported by said pivoted member and having a driving connection with the shaft and means interposed between said pivoted member and said traction wheel to prevent ingress of dust to the driving connection.

7. In combination with a vacuum cleaner, a nozzle portion having an opening adjacent a surface to be cleaned, a partition forming a chamber separate from the nozzle, a brush driving shaft having a bearing rigidly supported by the partition and projecting into the chamber, a flange on the shaft, a ring of fibrous material adapted to be retained between the shaft and the partition to retain lubricant and prevent the ingress of dust to the bearing, a circular member arranged to pivot about the axis of the shaft, means to maintain the circular member in a plurality of definite pivoted positions, a traction wheel having a flange, the wheel being supported by said circular member and arranged to drive the shaft and another ring of fibrous material interposed between said circular member and the flange of the wheel whereby a dust proof chamber is formed between the wheel and circular member for retaining lubricant for all the bearings and gears.

8. In combination with a vacuum cleaner nozzle having end and side walls, a partition having a removable portion extending across the nozzle near one end wall, a bearing adapted to support a brush driving shaft rigid with the removable portion, a circular member adjustably mounted to swing about the axis of such shaft and supported by the bearing, a traction wheel having a flange in overlapping relation with said cir-

cular member to form a casing for lubricant, a shaft and a gear rigidly supported by the wheel, said gear being arranged to drive the brush shaft and said wheel shaft being end-
wise removably supported in said circular member and means including a projecting portion of the wheel shaft arranged to contact with an adjacent end wall and thereby hold said wheel and circular member together when said removable partition portion is in place.

9. In a vacuum cleaner, a removably mounted brush, a shaft for rotating the brush, a bearing for the shaft comprising a plate rigid with the vacuum cleaner casing and a bearing member rigidly carried by the plate, a member having a circular peripheral surface supported by the bearing member and adapted to swing about the axis of the shaft, a traction wheel in eccentric relation to the said shaft and having a flange overlapping the circular surface to form a grease containing compartment, a dust ring interposed between said flange and surface, a geared connection between the wheel and the shaft within the compartment and means for raising and lowering traction wheel by shifting the circular member and holding it in shifted position.

10. In a device of the character described a housing having a portion thereof formed into a chamber open at the bottom, a removable plate arranged to be secured to the housing, a bearing carried thereby, and a brush driving shaft projecting therethrough and

extending within the chamber, a member for supporting a gear train and driving wheel adjustably pivoted about the axis of the shaft and within the chamber, a driving wheel and gear train carried thereby, said train being arranged to establish a driving connection between the wheel and shaft, the wheel and train being freely removable from the supporting member when the plate is removed from the housing and being retained in place by a wall of said housing when the plate is properly secured to the housing.

11. A vacuum cleaner brush gearing construction, comprising a housing member open at the bottom and having a partition thereacross, a plate secured to the housing and forming a part of such partition, a bearing and brush shaft carried thereby supported by the plate, a circular member adjustably pivoted about the axis of said shaft, a driving wheel having a peripheral flange, in overlapping relation with said circular member and forming therewith a lubricant containing casing, a gear train within said casing, one of the gears being rigid with the wheel, another being rigid with the shaft, said wheel being retained in telescoping relation with the circular member by a housing wall when the plate is properly secured in position and being freely removable therefrom when the plate is removed from the housing.

In testimony whereof, I hereunto affix my signature.

JULIUS KELLER, Sr.
